UNITED STATES PATENT OFFICE.

CLAUDE D. ENOCHS, OF LA CROSSE, WISCONSIN.

ELECTRICAL BALLAST-MOUNT.

No. 829,373.

Specification of Letters Patent.

Patented Aug. 21, 1906.

Application filed August 3, 1905. Serial No. 272,485.

To all whom it may concern.

Be it known that I, CLAUDE D. ENOCHS, a citizen of the United States, residing at La Crosse, in the county of La Crosse and State 5 of Wisconsin, have invented a new and useful Electrical Ballast-Mount, of which the following is a specification.

My invention relates to an electrical ballast-mount. Iron wire or other ballast conductors used in connection with telephone-exchange apparatus require to be supported in a manner in which they are not easily broken or do not fall apart by their own weight when heated.

15 The object of my invention is to provide means for supporting the ballast-conductor under varying conditions of load.

Further objects are simplicity of construction and effectiveness in use.

20 To these ends my invention consists, in a general way, of a mount of convenient shape, such as a stem around which is formed a spiral thread which receives and supports a ballast-conductor. This mount is provided 25 with lead-wires connected with the ballast-conductor and may be inclosed in a suitable sealed chamber, which may or may not contain an inert gas, as preferred.

In the accompanying drawings, forming 30 part of this specification, Figure 1 is a side view of my invention, showing part of the bulb broken away. Fig. 2 is a detail view of the stem holding the ballast-conductor, and Fig. 3 is a detail longitudinal section of the 35 stem.

In the drawings, A represents an ordinary lamp-bulb provided with a stem B, which is formed by a thin tube C or pencil of glass projecting therein. This thin tube or pencil 40 of glass before being attached to the bulb is wound spirally with a thin copper wire at a stated number of turns to the inch, care being taken that the wraps of wire do not touch. The tube with the copper wire wound upon it 45 is dipped in melted wax, and after the wax has hardened the wire is unwound, leaving a spiral thread of exposed glass upon the stem. The stem is then dipped in hydrofluoric acid, and the exposed glass is etched to any desired depth, leaving a spiral thread or groove 50 thereon. The wax is then removed and the ballast-conductor E, made of thin iron wire or other suitable material, wound in said spiral thread and attached to the leads 2 and 3,

which are connected with socket-terminals 4 55 and 5 on the bulb and sealed in said stem, as shown. The stem C is closed at its inner end, and a pair of small lugs 6 and 7 are formed on its surface and near each of its ends. The lead 2 is sealed in the upper lug 7 and connected to one terminal of the ballast-conductor. The opposite terminal of the ballast-conductor is hitched to the lug 6 and connected with the lead 3, as shown. The stem is sealed in the bulb A in the manner of 65 constructing incandescent lamps, and the bulb may be exhausted by attaching it to a receiver, after which it is closed in the ordinary way. By mounting the ballast-conductor upon the stem and fastening it in a 70 groove or otherwise said conductor can be heated to an extremely high temperature without falling apart by its own weight. In this manner the life and the efficiency of operation of the ballast-conductor are increased. 75

It is obvious that the form in which the ballast-conductor is wound and the shape of its supporting-stem may be changed or that it may or may not be used in connection with an outer inclosing bulb, as desired, without 80 departing from the spirit of this invention, and I do not wish to confine myself to the exact construction or use described.

Having described my invention, what I claim as new, and desire to protect by Letters Patent, is—

1. A mount for ballast-conductors, consisting of a stem threaded to receive the conductor and an inclosing chamber on which said stem is mounted.

2. A ballast-mount comprising a suitable support, having a spiral thread, and a ballast-conductor wound around said support and on said thread.

3. A device of the class set forth, comprising a stem of glass or other suitable material and a ballast-conductor wound around said stem, said stem provided with means for supporting said ballast-conductor throughout its entire length.

4. A device of the class set forth, comprising a ballast-conductor, a stem having means by which said conductor is supported throughout its entire length, an inclosing chamber in which said stem is mounted, and inleading electrical conductors connected with the terminals of said ballast-conductor.

5. A device of the class set forth, comprising

ing a stem having a spiral groove formed in its surface, a ballast-conductor wound in said groove, and a pair of electrical terminals connected in circuit with said ballast-conductor.

6. A device of the class set forth, comprising a suitable support, a ballast-conductor, an inclosing chamber containing said support and conductor, and a pair of leads connected in circuit with said conductor; said

support having an engagement to receive and hold said conductor throughout its length.

In testimony whereof I have signed my name to this specification in the presence of two subscribing witnesses.

CLAUDE D. ENOCHS.
